CLAIM

The ornamental design for a wedging cushion for spa cover section, substantially as shown and described.

DESCRIPTION

FIG. 1 is a perspective view of the wedging cushion;
FIG. 2 is a side view of the wedging cushion, the opposite side view being the same;

FIG. 3 is an end view of the wedging cushion, the opposite end view being a mirror image;

FIG. 4 is a top plan view of the wedging cushion; and,
FIG. 5 is a bottom plan view of the wedging cushion.
